Inventor:
Charles B. Spalsbury
by James R. Hodder
Atty.

UNITED STATES PATENT OFFICE.

CHARLES B. SPALSBURY, OF ST. LOUIS, MISSOURI, ASSIGNOR TO JOHNSON, STEPHENS AND SHINKLE SHOE COMPANY, OF ST. LOUIS, MISSOURI, A CORPORATION OF MISSOURI.

SIDE-LASTING MACHINE.

Application filed April 5, 1923. Serial No. 630,131.

To all whom it may concern:

Be it known that I, CHARLES B. SPALSBURY, a citizen of the United States, and resident of St. Louis, State of Missouri, have 5 invented an Improvement in Side-Lasting Machines, of which the following description, in connection with the accompanying drawings, is a specification, like letters on the drawings representing like parts.

10 In carrying out the manufacture of my novel type of shoe shown and described in my copending applications Ser. No. 555,588, filed April 19, 1922, and Ser. No. 566,496, filed June 7, 1922, it is desirable to provide 15 machine operations to last and trim the uppers, and my present invention is directed to a machine and method for this purpose.

In the single soled shoe construction of my prior applications, or the construction of 20 same with a plurality of layers united to constitute substantially a single sole, it is necessary to effect the lasting of the shoe upper into the marginal recess around the forepart of the sole. This operation involves the lasting and fitting of the upper 25 materials into a slot, groove, or recess in the sole, or laminated sole, about the forepart, and such upper materials must be trimmed, either before said lasting, after the 30 same, or substantially simultaneously therewith, in order to prevent bunching and objectionable ridges in the shoe. My present invention is a machine for effecting this trimming action substantially simultaneously, or immediately succeeding the side 35 lasting operation, and by means operable to effect the trimming action while the upper materials and insole are held under tension and in lasted position by the side lasting devices. This affords a very important advantage. It is, of course, necessary to have the lining and shoe upper, constituting the upper materials, to enable the lasting, stretching, and pulling of the same into position 40 snugly about the last with a surplus width or extent capable of being engaged by the side lasting devices and forced into lasted position around the margin of the sole of the improved shoe. Consequently it is very 45 difficult, and even impractical to trim the

upper materials to a proper extent prior to the lasting, so that no surplus bunching will be forced into the marginal groove or recess on the sole, particularly at the forepart. Therefore, this trimming action must 55 be performed, ordinarily, after the shoe is lasted. In my said prior applications this trimming was explained as being done by hand, and in the present application I accomplish this purpose automatically and by machine, substantially as a part of the lasting action.

Referring to the drawings, illustrating a preferred embodiment of the present invention and as applied to the side lasting machine and shoe of my prior application Ser. No. 555,588,

Fig. 1 is a plan view partly in cross-section, illustrating the trimming and lasting instrumentalities and means for operating 70 same;

Fig. 2 is a cross-sectional view on the line 2—2 of Fig. 1;

Fig. 3 is a side view;

Fig. 4 is a fragmentary view of the means 75 for actuating the trimming devices; and

Fig. 5 is a cross-sectional view on the line 5—5 of Fig. 1.

In the drawings I have illustrated in diagrammatic form my type of shoe as 80 assembled on a last 1 having a sole 2 and upper materials 3, the same being in lasted position with the upper 3 forced into the marginal grooves 4 of the sole 2, and held therein in lasted position by the side lasting devices 50, 85 50. These side lasting devices are preferably slotted at 51 to facilitate the driving of the lasting tacks through said slots from the marginal sections of the sole into the lasted upper, as explained in said prior applications. These side lasting devices are mounted in guideways 53, and are actuated substantially as shown in my said prior application, Serial No. 555,588. The upper engaging portions of the devices 50 may be serrated as illustrated at 52 for better engagement of the upper to pull, force, strain and last the same into the marginal groove 4 at each side of the forepart.

Mounted on the plane 55 carrying the de- 100

5 vices 50 is a slide 60, having secured at the forward end portion a trimming knife 61. This knife is continuous and is adapted to be moved forwardly over the slotted devices 50 to trim or cut the upper directly in the bottom of the recess 4, permitting the removal of the surplus material 13, and the withdrawal of the cutting knives prior to driving the lasting tacks through the slot 51, and hence while the lasting devices 50 are in position holding the upper in lasted position.

10 In order to effect a reciprocating movement of the cutting knives 61 forward and backwardly, I prefer to mount the same to slide relatively with the plate 55. To hold said knives firmly in position, I apply a cover 56 substantially co-extensive with the plate 55 and extending over the devices 50. 15 In fact I may make the cover plate 56 and devices 50 substantially equal with the slotted grooves 51 therethrough, working the cutting knife 61 therebetween and thus insuring the trimming of the upper materials 20 substantially midway of the depth of the slot in which they have been forced during lasting.

To effect this reciprocating action I provide an eccentric stud having its shank 20 threaded into the plate 55 and an eccentric 21 fitted thereon and engaging a corresponding slot 22 in said slide 60. Adjustment is afforded between the stud 20 and its eccentric 22 by means of a set screw 23. To hold 25 the same in assembled position I supply a handle 25 having thereon a hub 26, the latter of sufficient diameter to extend over and bear upon the cover or topmost portion 55. The hub 26 of the handle is keyed to the 30 shaft 20 as illustrated at 27. This construction affords sufficient throw to remove the knives 61 relatively with the slotted devices 50 into upper trimming and cutting position, beyond the edge of the said devices, 35 as shown in Fig. 2, and to retract the same to dotted line position illustrated in Fig. 1 at 63, thus clearing the slots 51 and permitting the driving of the lasting tracks through 40 said slots.

45 The operation of the machine will be readily appreciated. Upper and sole being assembled on the last, the side lasting devices 50 are manipulated to strain the upper materials over the last and then said devices 55 are moved forwardly to force, pull, and last the upper into the groove 4 along the forepart of the sole, holding the same in lasted position. Thereupon the handles 25 are manipulated to reciprocate the slide 60 and 60 knives 61, sliding or forcing them beyond the edges of the lasting devices, into trimming engagement with the upper, cutting the same at the extreme rear part as shown. The knives are thereupon withdrawn by reverse

65 movement of the handle 25 uncovering the slots 51, whereupon lasting tacks 70 are driven through said slots to retain the upper and sole in lasted position and the side lasting devices withdrawn and the shoe removed. 70

75 My present invention enables the trimming to be done accurately and instantly, and should the knives cut into the sole beyond the depth of the slot, no harm or difficulty will be experienced. In order to make the trimming knives readily removable and attachable to the slides 60, I provide screws 66 which still further enable the trimming knives to be changed in contour if necessary to operate on different styles and sizes of 80 footwear.

85 As clearly illustrated in Fig. 2, the top plate 55 and the bottom push devices 50, jam the upper materials into the slot of the sole, holding same stretched therebetween and permitting the cutting knife to function while the upper is thus held stretched at both sides, facilitating trimming, saving continual sharpening of knives, and effecting 90 a most satisfactory operation. In order to limit the forward movement of the slide 60 carrying the knife 61 I may add a stop at any desired point, and in any convenient manner, as for example a pin to limit the swing of the handles 25, such pin to be removable through different holes in the top plate 55 to limit the depth of cut of the trimming knife, as will be readily understood. 95

100 My invention is further described and defined in the form of claims as follows:

1. Apparatus for lasting and trimming shoe upper materials, comprising lasting devices adapted to engage, force, and hold upper materials into lasted position in the marginal recess of a shoe sole, upper trimming means mounted in said lasting devices and reciprocable longitudinally thereof, and means for reciprocating said trimming means while the lasting devices are held stationary whereby upper materials held in lasted position by the lasting devices are trimmed and cut. 110

115 2. In a machine for trimming surplus material from the uppers of boots and shoes after lasting, comprising means adapted to engage the upper materials in spaced relation, to hold the marginal edge of the upper to be removed and to hold the marginal edge of the upper to be retained in the shoe, in stretched and tensioned condition, and means operative, while the upper is so held, to cut the upper between said holding devices.

120 125 3. In a machine for trimming surplus material from the uppers of boots and shoes after the upper is placed in lasted position, comprising means adapted to engage the upper materials at a plurality of spaced

points for holding the marginal edge of the upper to be removed and for holding in stretched and tensioned condition the marginal edge of the upper that is to be retained in the shoe structure, and means slidably mounted for reciprocating movement in said engaging means to cut the upper at the

junction of the marginal edge of the upper to be removed and the marginal edge of the upper to be retained.

In testimony whereof, I have signed my name to this specification.

CHAS. B. SPALSBURY.
